(57) **CLAIM**

The ornamental design for a LED lighting, as shown and described.

DESCRIPTION

FIG. 1 is a perspective view of a first embodiment of a LED lighting.

FIG. 2 is a front view of the first embodiment of the LED lighting.

FIG. 3 is a rear view of the first embodiment of the LED lighting.

FIG. 4 is a left-side view of the first embodiment of the LED lighting, the right-side view being symmetric with respect to the left-side view; and,

FIG. 5 is a top view of the first embodiment of the LED lighting, the bottom view being symmetric with respect to the top view.
